BOOKBINDING MACHINE

Elbridge W. Palmer and Herman L. Beutler,
Kingsport, Tenn., assignors to Kingsport Press,
Inc., Kingsport, Tenn., a corporation of Delaware

Application October 29, 1940, Serial No. 363,285

12 Claims. (Cl. 11—1)

Our invention consists in a novel and efficient machine for attaching end sheets to book bodies which have been previously provided with hinge strips having overlapping and free portions; said 5 machine including, generally, the following operative elements: means for advancing successive book bodies along a suitable support; means for gumming portions along the two leaves of a folded end sheet, the gummed portion of one leaf being adapted to be adhered to the overlapping portion of a hinge strip on one side of a book body; means for folding the free portion of the hinge strip over onto the gummed portion of the other leaf of the folded end sheet and adhering it thereto.

Our invention may also include means for reversing each book body after the folded end sheet has been secured to one side thereof and means for conveying each book body into position where another set of operative elements may be employed for repeating the folded end sheet attaching operations on the opposite side of each book body.

Our invention more specifically comprises, in 25 one instance, means for gumming the leaves of a folded end sheet along opposite sides of the folded outer edge of the sheet, and in another instance gumming the leaves along the free edges thereof.

30 Our invention further comprises in one instance means for gumming narrow and wide portions on the leaves along the opposite sides of the folded outer edge of the folded end sheet so that the narrow gummed portion of one leaf may be adhered to the narrow overlapping portion of a hinge strip and the wide free portion of the hinge strip may be adhered to the wide gummed portion of the other leaf.

Our invention further comprises in another 40 instance means for gumming narrow portions along leaves of an off-middle folded end sheet whereby the narrow gummed portion along the wide leaf may be adhered to the narrow overlapping portion of a hinge strip and the wide free portion of the hinge strip may be adhered to the narrow gummed portion of the narrow leaf.

Our invention further comprises means for 45 simultaneously gumming the leaves of a folded end sheet, either upon opposite sides of its folded edge in one instance or along the free edges of the leaves in another instance.

The method which is shown and described 50 herein forms the subject matter of our co-pend-

ing application filed of even date herewith, its Serial No. being 363,284.

In the accompanying drawings,

Fig. 1 represents a top plan view of the machine;

Fig. 2 represents a side elevation of the same;

Fig. 3 represents a detail section of the book body reversing means;

Fig. 4 represents a side elevation of the gummer on an enlarged scale;

Fig. 5 represents an end view of the same;

Fig. 6 represents a section showing the means for folding over the free portion of the hinge strip;

Fig. 7 represents a plan view of the same;

Fig. 8 represents a transverse vertical section taken in the plane of the line VIII—VIII of Fig. 6;

Fig. 9 represents a top plan view of the guide for turning the free portion of the upper hinge strip;

Fig. 10 represents a side elevation of the same;

Fig. 11 represents an end view of the same;

Fig. 12 represents a plan view of one of the leaves of a middle folded end sheet with the band of gum applied to its outer face along its folded edge;

Fig. 13 represents an end view of the same;

Fig. 14 represents a plan view of the other leaf of the middle folded end sheet with a wider band of gum applied to its outer face;

Fig. 15 represents a view similar to Fig. 12 of an off-middle folded end sheet with the outer face of one leaf provided with a narrow band of gum along its free edge;

Fig. 16 represents an end view of the same;

Fig. 17 represents a view similar to Fig. 14 showing the off-middle folded end sheet with a narrow band of gum applied to the free edge of the exposed leaf;

Fig. 18 represents a detail section of the upper and lower gumming rollers with a scraper provided for the wide lower roller; and

Fig. 19 represents a detail horizontal section taken in the plane of the line XIX—XIX of Fig. 18.

The book bodies 1 are each provided on both sides with hinge strips which are shown herein as having narrow overlapping attached portions 2 and wide free portions 3.

The end sheets are shown in one embodiment as folded in the middle to form equal width leaves 4 and 5 and in the other embodiment as folded off the middle to form wide and narrow leaves 6 and 7 respectively. It is understood that

55

the leaves 4 and 5 of the middle folded end sheets are intended to be adhered along their outer faces on opposite sides of the fold to the hinge strips and thereby conceal the hinge strips to form 5 so-called "closed joints"; while the leaves 6 and 7 of the off-middle folded end sheets are intended to be adhered respectively along their outer faces at their free edges to the overlapping and free portions of the hinge strips and thereby expose 10 portion of the hinge strips and form so-called "open joints."

The outer faces of the leaves 4 and 5 of the middle folded end sheets may be provided with narrow and wide bands 8 and 9 respectively of 15 gum upon opposite sides of the fold, and the outer faces of the leaves 6 and 7 of the off-middle folded end sheets may be provided with narrow bands 10 and 11 respectively of gum along 20 their free edge portions; it being understood that in this latter instance the folded edge of the end sheet may be subsequently trimmed with the edges of the book body, to form two separated leaves.

The machine comprises, generally, a supporting table; means for supplying successive book bodies provided with hinge strips; means for intermittently advancing the book bodies successively from their magazine; means for supplying folded end sheets for attachment to the 30 hinge strips on one side of the book bodies; means for applying gum, preferably, simultaneously, to the outer faces of the leaves of the folded end sheets along the desired portions thereof; means for folding the free edges of the hinge strips over 35 onto the gummed portions of the upper leaves of the folded end sheets after the gummed portions of the lower leaves have been applied to the overlapping attached portions of the hinge strips; and means for applying sealing pressure 40 to ensure a complete attachment of the end sheets to the hinge strips.

Where it is desired to attach the folded end sheets to the other side of the book bodies by other apparatus in the same machine, the machine will include beside the means already set forth: means for reversing the book bodies and means for conveying the reversed book bodies into position to have the folded end sheets attached to their other side; it being understood 45 that in this instance there are provided: a second means for advancing the book bodies; a second means for supplying folded end sheets; a second means for applying gum, preferably, simultaneously, to the outer faces of the leaves 50 of the folded end sheets; a second means for folding the free edges of the hinge strips over onto the exposed gummed portions of the upper leaves of the folded end sheets after the gummed portions of the lower leaves have been applied 55 to the overlapping attached portions of the hinge strips; and a second means for applying sealing pressure to ensure the even attachment of the end leaves to the hinge strips.

The table for supporting the several elements 60 is denoted by 12. The magazine 13 serves as a means for supplying successive book bodies. The longitudinally disposed endless carrier 14 is arranged to receive successive book bodies from the magazine 13 and intermittently advance the book bodies along the table 12. A magazine 15 serves 65 as a source of supply for the folded end sheets.

The means for simultaneously applying gum to the outer faces of the leaves of the folded end sheets along the desired portions thereof is here- 70 in shown as a gummer 16 comprising upper and

lower gumming rollers 17 and 18 and their gum supply fountains 19 and 20. The narrow upper roller 17 is shown as adapted to gum a narrow band on the outer face of one leaf of a folded end sheet and the wide lower roller 18 is shown wide enough to gum a wide band on the outer face of the other leaf. A scraper 21 may be used in connection with the wide roller 18 to control the width of the band of gum applied thereby. For instance, the two gumming rollers 10 when used without the scraper are arranged to gum the outer faces with narrow and wide bands upon opposite sides of the folded edge of a middle folded end sheet. Where the scraper 21 is used in connection with the wide lower gumming 15 roller 18, narrow bands may be gummed on the outer faces of the two leaves of an off-middle folded end sheet at their free edges.

The means for folding the free edges of the hinge strips over onto the exposed gummed portion of the upper leaf of the folded end sheet after the gummed portion of the lower leaf has been adhered to the overlapping portion of the hinge strips by the operator, is shown as comprising a folder bar 22 manually operated from 25 a foot lever 23 suitably placed for the convenience of the operator.

The means for applying sealing pressure to the attached portions of the end sheets and hinge strips may comprise a series of pairs of pressure rollers 24, 24' between which the book bodies with their attached end leaves are passed, to ensure an even sealing of the end leaves to the hinge strips. Where the end sheet applying operations are to be repeated by duplicate apparatus in the same machine we preferably provide a hinged plate 25 onto which the book bodies are successively pushed by their preceding book bodies. The hinged plate 25 may be swung to reverse the books as follows: a spring pressed 40 tripping finger 26 projects in position to be operated by the leading book body as it arrives on the reversing plate 25, thus forcing the finger away from its normal position and thereby bringing its rotating clutch member 27 into engagement with the normally idle clutch member 28 which may be provided with a rotary segment 29 adapted in its rotary movement to mesh with a segment 30 on the hinge of the reversing plate 25 and thus swing the plate upwardly and over 50 a sufficient distance to reverse the book body and deposit it on a laterally disposed endless carrier. The plate may be returned to its normal horizontal position by the weight 31 and its connection 32 as soon as the segment 29 leaves the 55 segment 30. As soon as pressure is released from the tripping finger 26 the finger will return to its normal position and its rotating clutch member 27 separated from the clutch member 28.

A laterally disposed endless carrier is denoted 60 by 33 and it is arranged to convey the reversed book bodies laterally into position to be engaged and advanced by a second longitudinally disposed endless carrier 34. The reversed book body may then be subjected to the end sheet applying operations by the use of the second folded end sheet supply magazine 35, the second gummer 36, the second folder 37 and the second sealing pressure means 38.

A common drive, such as a motor 39, may be 70 provided for operating the first and second longitudinally disposed endless carriers, the laterally disposed endless carrier, the first and second gummers, the first and second pressure applying means and the book body reversing means. 75

In the present instance the motor 39 is shown as operatively connected to the first longitudinally disposed endless carrier 14 by the double pulley 40, belt 41, pulley 42, cross shaft 43, bevel gears 44, 45, shaft 46, bevel gears 47, 48 and shaft 49. This motor 39 is shown as operatively connected to the second longitudinally disposed endless carrier 34 by the double pulley 40, belt 50, pulley 51, cross shaft 52, bevel gears 53, 54, shaft 55, bevel gears 56, 57 and shaft 58.

The motor 39 is shown as operatively connected to the first gummer 16 through the pulley 59, cross belt 60 and pulley 61 on the cross shaft 62 of the lower wide faced gumming roller 18 which may drive the upper narrow gumming roller 17 through the gears 63, 64.

The second gummer 36 may be driven from the cross shaft 52 through the pulley 65, belt 66 and pulley 67 on the shaft of the lower wide faced gumming roller 18.

The lower rollers 24' of the first sealing pressure means may be driven from the cross shaft 52 through the train of gears 68. Similarly, the lower rollers of the second sealing pressure means 38 may be driven from the cross shaft 43 through the train of gears 69. The laterally disposed endless carrier 33 may be driven from the cross shaft 52 through the bevel gears 70, 71, shaft 72, spur gears 73 and shaft 74.

The clutch member 27 of the book body reversing means may be driven from the shaft 14 through the train of gears 75.

A floor guide 76 may be provided for turning the free portion 3 of the upper hinge strip upwardly into position to be engaged and turned over by the manually operated folder bar 22.

It is evident that various changes may be resorted to in the construction, form and arrangement of the several parts without departing from the spirit and scope of our invention, and hence we do not intend to be limited to the particular embodiment herein shown and described, but

What we claim is:

1. A machine for attaching end sheets to book bodies provided with hinge strips having overlapping and free portions, including, means for advancing a book body, means for gumming portions along the outer faces of the leaves of a folded end sheet, and means for folding the free portion of the hinge strip and for adhering the gummed portions of the leaves to the overlapping and folded free portions respectively of the hinge strip.

2. A machine for attaching end sheets to book bodies provided with hinge strips having overlapping and free portions, including, means for advancing a book body, means for gumming portions along the outer faces of the leaves of a folded end sheet, means for folding the free portion of the hinge strip and for adhering the gummed portions of the leaves to the overlapping and folded free portions respectively of the hinge strip, and additional pressure means for ensuring the even attachment of the end sheet to the hinge strip.

3. A machine for attaching end sheets to book bodies provided with hinge strips having overlapping and free portions, including, means for advancing a book body, means for simultaneously gumming portions along the outer faces of the leaves of a folded end sheet, and means for folding the free portion of the hinge strip and for adhering the gummed portions of the leaves to the overlapping and folded free portions respectively of the hinge strip.

4. A machine for attaching end sheets to book bodies provided with hinge strips having overlapping and free portions, including, means for advancing a book body, means for gumming portions along the outer faces of the leaves of a folded end sheet upon opposite sides of its folded edge, and means for folding the free portion of the hinge strip and for adhering the gummed portions of the leaves to the overlapping and folded free portions respectively of the hinge strip.

5. A machine for attaching end sheets to book bodies provided with hinge strips having overlapping and free portions, including, means for advancing a book body, means for gumming portions along the outer faces at the free edges of the leaves of a folded end sheet, and means for folding the free portion of the hinge strip and for adhering the gummed portions of the leaves to the overlapping and folded free portions respectively of the hinge strip.

6. A machine for attaching end sheets to book bodies provided with hinge strips having overlapping and free portions, including, means for advancing a book body, means for gumming portions along the outer faces of wide and narrow leaves of an off-middle folded end sheet at their free edges, and means for folding the free portion of the hinge strip and for adhering the gummed portions of the wide and narrow leaves to the overlapping and folded free portions respectively of the hinge strip.

7. A machine for attaching end sheets to book bodies provided with hinge strips having overlapping and free portions, including, means for gumming portions along the outer faces of the leaves of a folded end sheet, means for adhering the gummed portions of the leaves to the overlapping and free portions respectively of the hinge strip, means for reversing the book body, and means for repeating the end sheet applying operations.

8. A machine for attaching end sheets to book bodies provided with hinge strips having overlapping and free portions, including, means for gumming portions along the outer faces of the leaves of a folded end sheet, means for adhering the gummed portions of the leaves to the overlapping and free portions respectively of the hinge strip, means for reversing the book body, means for conveying it to a predetermined position, and means for repeating the end sheet applying operations.

9. A machine for attaching end sheets to book bodies provided with hinge strips having overlapping and free portions, including, means for advancing a book body, means for gumming portions along the outer faces of the leaves of a folded end sheet, means for folding the free portion of the hinge strip and for adhering the gummed portions of the leaves to the overlapping and folded free portions respectively of the hinge strip, means for reversing the book body, and means for repeating the end sheet applying operations.

10. A machine for attaching end sheets to book bodies provided with hinge strips having overlapping and free portions, including, means for advancing a book body, means for gumming portions along the outer faces of the leaves of a folded end sheet, means for folding the free portion of the hinge strip and for adhering the gummed portions of the leaves to the overlapping and folded free portions respectively of the hinge strip, additional pressure means for en-

- suring the even attachment of the end sheet to the hinge strip, means for reversing the book body, and means for repeating the end sheet applying operations.
- 5 11. A machine for attaching end sheets to book bodies provided with hinge strips having overlapping and free portions, including, means for advancing a book body, means for gumming portions along the outer faces of the leaves of a folded end sheet, means for folding the free portion of the hinge strip and for adhering the gummed portions of the leaves to the overlapping and folded free portions respectively of the hinge strip, means for reversing the book body, means 10 for conveying it to a predetermined position, and means for repeating the end sheet applying operations.
12. A machine for attaching end sheets to book bodies provided with hinge strips having overlapping and free portions, including, means for advancing a book body, means for gumming portions along the outer faces of the leaves of a folded end sheet, means for folding the free portion of the hinge strip and for adhering the gummed portions of the leaves to the overlapping and folded free portions respectively of the hinge strip, additional pressure means for ensuring the even attachment of the end sheet to the hinge strip, means for reversing the book body, means for conveying it to a predetermined position, and means for repeating the end sheet applying operations. 15
